United States Patent

Des. 242,477

Patented Nov. 23, 1976

242,477

HAND PUPPET

Judith L. Folkmanis, 2212 Roosevelt Ave.,
Berkeley, Calif. 94703

Filed June 13, 1975, Ser. No. 586,492

Term of patent 14 years

Int. Cl. D21—01

U.S. Cl. D34—2 C

FIG. 4

FIG. 5

FIG. 1 is a side elevational view of a hand puppet showing my new design;

FIG. 2 is a front elevational view thereof;

FIG. 3 is a top plan view thereof;

FIG. 4 is a rear elevational view thereof; and

FIG. 5 is a bottom plan view thereof.

I claim:

The ornamental design for a hand puppet, as shown and described.
